FIRE EXTINGUISHING APPARATUS

Howard Edwin Bedford and Arthur Hall, Brentford, England, assignors to Pyrene Manufacturing Company, Newark, N. J., a corporation of Delaware

Original application November 20, 1946, Serial No. 61,668, now Patent No. 2,532,986, dated December 5, 1950. Divided and this application November 23, 1948, Serial No. 61,668. In Great Britain November 7, 1945.

1 Claim. (Cl. 261—116)

1
This invention relates to fire extinguishing apparatus, and more particularly to apparatus that can be changed or adjusted quickly to deliver either fire extinguishing foam or a simple stream of fire extinguishing liquid such as water.

The production of what is commonly known as air foam or mechanical foam is now well understood in the fire extinguishing field, and such foam is used extensively for putting out fires, particularly those involving inflammable liquids such as oil, gasoline, and the like. The apparatus used for producing this air foam usually consists of a device in which water under pressure and carrying a foam stabilizing compound is projected in one or more jets into one or more receivers in such a manner as to entrain or aspirate air into the stream by ejector action. The turbulent mixture of air, water and foam stabilizing agent thus formed becomes foam by the time it reaches the end of the hose or pipe used for directing it on the fire.

In many instances it is desirable to apply foam to one portion of a fire, and when this portion is under control to deal with other portions of the fire by means of an ordinary stream of water. In most forms of foam producing apparatus, the velocity at which the foam is delivered, or the throw of the foam, is considerably restricted by reason of the fact that some of the energy of the original stream of water under pressure is used up in producing the foam. Consequently, if the supply of air in such an apparatus were merely cut off, the stream of water thus obtained from the apparatus would not have much force because the pressure of the initial stream of water would not be utilized to best advantage. Also, the stream would be smaller in size than would be desirable.

One object of this invention is to provide apparatus which can be quickly changed from an apparatus for producing and delivering fire extinguishing foam to an apparatus for delivering a substantially full size stream of water.

Another object of the invention is to provide foam making apparatus of this type in which the means for producing the aspirating jets of liquid can be moved to allow greater flow of the liquid.

Other objects and advantages of our invention will be explained and will be apparent from the following description of an embodiment of the apparatus illustrated in the accompanying drawings, in which

Fig. 1 is a fragmentary longitudinal sectional view through the center of apparatus illustrating an embodiment of our invention.

Fig. 2 is a vertical sectional view taken on the line 11—11 of Fig. 1.

Fig. 3 is a vertical sectional view taken on the line 2—2 of Fig. 1.

Fig. 4 is a vertical sectional view taken on the line 3—3 of Fig. 1.

Fig. 5 is a vertical sectional view taken on the line 4—4 of Fig. 1.

Fig. 6 is a vertical sectional view taken on the line 5—5 of Fig. 1.

Fig. 7 is a vertical sectional view taken on the line 6—6 of Fig. 1.

Fig. 8 is a vertical sectional view taken on the line 7—7 of Fig. 1.

Fig. 9 is a vertical sectional view taken on the line 8—8 of Fig. 1.

Fig. 10 is a vertical sectional view taken on the line 9—9 of Fig. 1.

Fig. 11 is a vertical sectional view taken on the line 10—10 of Fig. 1.

Fig. 12 is a vertical sectional view taken on the line 11—11 of Fig. 1.

Fig. 13 is a vertical sectional view taken on the line 12—12 of Fig. 1.

Fig. 14 is a vertical sectional view taken on the line 13—13 of Fig. 1.

Fig. 15 is a vertical sectional view taken on the line 14—14 of Fig. 1.

Fig. 16 is a vertical sectional view taken on the line 15—15 of Fig. 1.

Fig. 17 is a vertical sectional view taken on the line 16—16 of Fig. 1.

Fig. 18 is a vertical sectional view taken on the line 17—17 of Fig. 1.

Fig. 19 is a vertical sectional view taken on the line 18—18 of Fig. 1.

Fig. 20 is a vertical sectional view taken on the line 19—19 of Fig. 1.

Fig. 21 is a vertical sectional view taken on the line 20—20 of Fig. 1.

Fig. 22 is a vertical sectional view taken on the line 21—21 of Fig. 1.

Fig. 23 is a vertical sectional view taken on the line 22—22 of Fig. 1.

Fig. 24 is a vertical sectional view taken on the line 23—23 of Fig. 1.

Fig. 25 is a vertical sectional view taken on the line 24—24 of Fig. 1.

Fig. 26 is a vertical sectional view taken on the line 25—25 of Fig. 1.

Fig. 27 is a vertical sectional view taken on the line 26—26 of Fig. 1.

Fig. 28 is a vertical sectional view taken on the line 27—27 of Fig. 1.

Fig. 29 is a vertical sectional view taken on the line 28—28 of Fig. 1.

Fig. 30 is a vertical sectional view taken on the line 29—29 of Fig. 1.

Fig. 31 is a vertical sectional view taken on the line 30—30 of Fig. 1.

Fig. 32 is a vertical sectional view taken on the line 31—31 of Fig. 1.

Fig. 33 is a vertical sectional view taken on the line 32—32 of Fig. 1.

Fig. 34 is a vertical sectional view taken on the line 33—33 of Fig. 1.

Fig. 35 is a vertical sectional view taken on the line 34—34 of Fig. 1.

Fig. 36 is a vertical sectional view taken on the line 35—35 of Fig. 1.

Fig. 37 is a vertical sectional view taken on the line 36—36 of Fig. 1.

Fig. 38 is a vertical sectional view taken on the line 37—37 of Fig. 1.

Fig. 39 is a vertical sectional view taken on the line 38—38 of Fig. 1.

Fig. 40 is a vertical sectional view taken on the line 39—39 of Fig. 1.

Fig. 41 is a vertical sectional view taken on the line 40—40 of Fig. 1.

Fig. 42 is a vertical sectional view taken on the line 41—41 of Fig. 1.

apparent, of course, that when the apparatus is used to deliver a stream of water, the various joints must be tight to prevent loss of water.

The terms and expressions which we have employed are used as terms of description and not of limitation, and we have no intention, in the use of such terms and expressions, of excluding any equivalents of the features shown and described or portions thereof, but recognize that various modifications are possible within the scope of the invention claimed.

This application is a division of our parent application Serial No. 711,170 filed November 20, 1946, now Patent No. 2,532,986 of December 5, 1950.

We claim:

Fire extinguishing apparatus for producing foam or a stream of liquid comprising a tubular receiver tapered toward its outlet end and having openings near its entrance end for admitting aspirated air under atmospheric pressure, a conduit joined to said entrance end for supplying fire extinguishing liquid under pressure, a series of ports between said conduit and receiver for directing converging streams of liquid into said receiver, a valve for controlling liquid flow through said ports, means for actuating said

valve to one position for opening all of said ports, and into a second position for closing only certain of said ports, the proportions of said ports, receiver and openings being such as to aspirate air through said openings to produce foam in said receiver when certain only of said ports are open, and to increase the flow of liquid to substantially fill said receiver when all of said ports are open to thereby lessen the aspirating effect to such an extent as to produce a stream of liquid.

HOWARD EDWIN BEDFORD.
ARTHUR HALL.
